UNITED STATES PATENT OFFICE

WALTER EVERETT MOLINS, OF DEPTFORD, LONDON, ENGLAND

PRINTING MACHINE

Application filed May 29, 1929, Serial No. 367,075, and in Great Britain June 21, 1928.

This invention is for improvements in or relating to a method of and means for printing labels and the like, and has for its object the provision of means whereby multi-colour impressions may be imprinted upon a label or card at a high speed upon a machine of limited dimensions possessing the necessary means whereby one colour impression may be dried before the material is subjected to the

10 next printing operation.

The present invention consists of a multi-colour printing machine wherein successive sheets of paper, cardboard or the like are fed through two or more printing units in such 15 a manner that the speed of movement of each sheet between successive units is less than the speed of movement of the sheet through the said units.

The invention will be more particularly 20 described with reference to the accompanying drawings, in which:—

Fig. 1 shows diagrammatically a four colour printing machine constructed according to this invention.

25 Fig. 2 shows a section to a larger scale of the sheet cutting mechanism.

Fig. 3 shows a plan view of a detail of Fig. 2.

Fig. 4 shows a detail of Fig. 2, and

30 Fig. 5 shows a section to a large scale of one printing and stacking unit, together with the associated transfer mechanism.

Fig. 6 shows a sectional elevation of a portion of Fig. 3 in the direction of the arrow

35 "A".

Referring to Fig. 1, a paper web 1 is fed from a reel 2 rotatably mounted on the frame 3 of the machine, and is arranged to pass through a device 4 operable to remove any 40 curl which may exist in the paper. The paper is thereafter led through a cleaner composed of two rotary brushes 5 into a cutting mechanism 6 operable to sever the web into separate sheets of the required length.

45 The sheets are transferred from the mechanism 6 through the first printing unit 7, and each printed sheet is thereafter fed to the upper end of a stacking device 8 which is operable to convey the same downwardly to the lower end thereof from which the sheet

is removed by a transferring apparatus 9 to the next printing unit 10. The printed sheet from the printing unit 10 is received by a second stacking device 11 and is moved upwardly thereby into proximity with a further transferring apparatus which feeds the sheet to another printing unit. Thus it will be seen that the sheet follows a staggered path through the printing machine.

55 The machine may comprise further printing units and stacking devices and transferring apparatus similar to those hereinbefore described, and the number of such units, device and apparatus depends upon the number of colours to be printed, but it will be observed that the sheets are moved in a substantially sinusoidal path through the machine for the purpose of ensuring that a sufficient time interval elapses between each printing operation to enable the sheet to dry.

60 After a sheet has been printed in the various colours, the same may be transferred to any desired cutting or embossing apparatus for further treatment.

65 Referring to Fig. 2, which shows in detail the apparatus employed for severing the web into sheets, the paper web 1 is fed beneath a roller 13 and between a pair of feed rollers 14 and 15. The rollers 14 and 15 feed the web to a cutting mechanism comprising an upper roller 16 furnished with a blade 17 and a lower roller 18 which is furnished with a blade 18^a which co-operates with the blade 17.

70 The web from the rollers 16 and 18 is fed to a further pair of rollers 19 and 20 which are rotated at a higher peripheral speed than the rollers 16 and 18 in order to draw the cut sheet away from the remainder of the web.

75 The mechanism shown at the righthand end of Fig. 2 is provided for the purpose of preventing a ragged end of a web from passing through the machine.

80 This apparatus comprises a roller 13 mounted upon an arm 13^a pivoted at 21 and pressed downwardly by a spring 22.

85 A pair of rollers 23 are mounted on the lower shaft and spaced apart as shown in Fig. 3 so that the upper roller can pass down between the same when there is no paper present. Thus, if the web of paper should

55

100

break, the roller 13 will be moved downwardly under the action of the spring 22 as the broken end passes into the machine, and a roller 24 at the opposite end of the arm 13^a will rise and lift the hook shaped piece 25 into the path of the pawl 26.

A cam 27 provided with a series of faces, for example three, is adapted to oscillate a bell crank lever 28, the free end of which carries the hook shaped piece 25.

When the piece 25 is moved upwardly by the roller 24 the next face of the cam 27 will cause the hook 25 to come into contact with the pawl 26. The pawl 26 is pivoted to a lever 29 (see Fig. 4) which is pivoted to the bearing 29^a carrying the upper feed roller 14, and the lever 29 is also fixed to a cam block 30 provided with two flats.

In the normal position the cam block is resting as shown in Fig. 4 on a cross piece 31 which is fixed to the frame of the machine, but when the pawl 26 is operated by the hook 25 the cam 30 and the bearing block are lifted against the action of the roller springs 32 and the cam rotates with the lever 29 about its pivot so that the other flat face of the cam block rests on the cross piece 31 and the upper roller 14 is therefore held out of contact with the lower roller.

The above action causes the feed of the broken end of the web to cease, and as soon as the cutting knives have separated this ragged portion from the preceding blank, the same will drop downwardly between the first two sets of rollers or rest between the said rollers until it is removed by the operator.

By providing the cam 27 with a series of faces as shown, the rollers 14 are lifted almost immediately a breakage has occurred as the faces are spaced apart a distance equal to one-third of a blank length.

It may happen that a broken piece of paper may pass between the cutting rollers owing to the fact that the same may catch on some portion of the rollers, and when this occurs, the broken piece is deflected downwardly in a manner hereinafter described.

As soon as the web is drawn through the rollers 13 and 23 by the operator in re-starting the machine, the roller 13 is lifted and the pawl 25 is restored to its former position by the operator, and the rollers 14 and 15 continue to feed the web until a fresh break occurs.

The rollers 19 and 20 rotate at a higher speed than the rollers 16 and 18, and in order to prevent the blank from being torn the roller 19 is lifted out of engagement with the roller 20 while the leading end of the blank passes between the pair of rollers by means of a cam 32.

When the roller 19 falls on to the surface of the blank, the latter is speedily withdrawn from the leading edge of the following web

and the blank passes between a pair of guides 33.

In order to ensure that the blank shall be in correct register throughout the printing process, the blanks are fed to each printing unit by means of reciprocating arms. In the present instance the arm comprises a hook shaped member 34 pivotally secured to an arm 35 which is oscillated against the action of spring 37 by a cam 36 mounted upon a spindle 36^a.

The arm 34 is held in engagement with the blank by means of an oscillating carriage 38 which is rocked up and down by a cam 39 mounted on the spindle 36^a.

On the working stroke of the arm 34 the carriage is in the position shown in Fig. 2, and the arm 34 lies parallel to the blank, but on the inward stroke of the arm 34 the carriage is supported by the lower portion of the cam 39 and the pawl 34 drops clear from the path of the oncoming blank.

When the machine is started up or re-started after a break, the leading blank may be shorter than is required, and in order to deflect this defective blank from the machine there is mounted in front of the rollers 19 and 20 a pair of rollers 40 which are spaced apart on their spindle and beneath them is mounted an oscillating finger 41 which is periodically raised by a cam 42 immediately after the moment when the leading edge of a blank comes under the rollers 40.

If the blank is shorter than usual, the leading edge thereof will not be at the required position beneath the rollers 40 at the correct time, and the oscillating finger 41 will prevent it from passing beneath the rollers 19 and 20 and deflect it downwardly in front of the pawl 41.

The same action takes place whenever a broken piece of paper passes between the cutting rollers in the manner previously mentioned.

The pawl 41 is provided with a spring tip on its working end, and when a normal blank is passing through, the spring will give so that the tip does not bend or distort the paper.

Referring to Fig. 3, the blank after passing between the guides 33 is fed between a printing roller 43 and a pressure roller 44.

The printing roller comprises an intaglio engraved roller of the usual kind and is arranged to rotate in a bath of ink 45 and is furnished with a reciprocating doctor blade 46. The blank passes from the printing apparatus to a pair of feed rollers 47 and 48 which are in the form of a pair of thin discs mounted on the spindle as shown, and arranged so that they contact with the blank on the unprinted margins thereof. The blank is moved from the grip of the rollers 47 and 48 by a cam operated arm 49 and fed on to the surface of movable guides 50.

The guides 50 are operated by cams 51

through levers 52 (see Fig. 6) so that as the blank runs on to them they are spaced apart the width of the blank, and as soon as the blank reaches the forward guide 53 of the magazine the guides 50 open outwardly and the blank drops on to the upper surface of the spirals 54. The spirals 54 are rotated by gearing (not shown) and the blank passes downwardly in the manner shown in Fig. 5 between the guides 53 and a rear guide 55.

When the blank reaches the bottom of the spirals the same is lowered on to a pair of guide members 56 and by this time the ink is quite dry.

15 A pusher piece 57 on a chain conveyor 58 carries the blank partly along the guides 56 and the cam operated arm 59 transfers the blank to a printing unit identical in construction with the one previously described.

20 By using the feed arms such as 34 and 59 throughout the machine it is possible to ensure that one impression is in perfect register with the previous printed impression as the blanks are always located from the same edge.

25 After the blank has passed through this second printing unit the same is moved upwardly through a spiral stacker of exactly the same construction as the one shown in Fig. 3 and the process is repeated as many times as may be necessary.

30 When the machine is working on comparatively thick pasteboard the printing rollers and their pressure rollers are not in contact, but when the machine is working on thin paper the pair of rollers must be in contact, and in order to prevent off set whenever a blank is missing, or the machine is being run empty in starting up, the arrangement shown at the right hand side of Fig. 2 may be duplicated at each printing unit so that until a blank has passed through the detector rollers 13 and 23 the upper roller will be held away from the lower roller.

35 The operation of the machine as designed above is unaffected by the cumulative stretch or shrinkage which occurs in a continuous web by changing atmospheric conditions or by changing tension in the web.

40 Further, the printing rollers may be of constant diameter, and need not of necessity be of the exact circumferential development required in printing from the continuous web.

45 Thus, as the rollers wear they may be ground and re-engraved, whereas with printing from a continuous web, the same is not possible.

50 It will be appreciated that the machine can be employed in conjunction with sheets previously severed and fed separately to the first printing unit, and successive printed sheets may be stacked in piles at the conclusion of the printing operations.

55 Thus it will be seen that according to the present invention there is provided a machine wherein the printed sheets are alter-

nately fed in reverse directions to successive printing units arranged in different planes.

What I claim as my invention and desire to secure by Letters Patent is:—

1. In a printing machine, the combination with a plurality of printing units, of means for feeding sheets through said units at relatively high speed, and means for supporting two opposite edges of each sheet and conveying the same at a reduced speed from one to another of said printing units. 70

2. In a printing machine, the combination with a plurality of printing units, of means for feeding sheets through said units at relatively high speed, and means for engaging each sheet at spaced points adjacent opposite edges thereof for supporting and conveying the same at a reduced speed from one to another of said printing units. 80

3. In a printing machine, the combination with a plurality of printing units, of means for feeding sheets through said units at relatively high speed, and means for receiving and conveying said sheets in superposed relationship and at a reduced speed from one to another of said printing units. 85

4. In a printing machine, the combination with a plurality of printing units arranged at substantially different levels, of means for feeding sheets through each unit at relatively high speed, and means for conveying said sheets at a reduced speed from one to another of said units. 95

5. In a printing machine, the combination with a plurality of printing units arranged at substantially different levels, of means for feeding sheets through each unit at relatively high speed in a horizontal direction, and a conveyer for moving said sheets in a vertical direction and in superposed relation at reduced speed from one to another of said units. 100

6. In a printing machine, the combination with a plurality of printing units, of means for feeding sheets through said units at relatively high speed, and means for receiving and conveying said sheets in superposed relationship and at a reduced speed from one to another of said printing units, said last named means comprising a plurality of rotating elements having threaded portions arranged to engage the edges of the sheets. 110

7. In a printing machine, the combination with a plurality of printing units arranged at substantially different levels, of means for feeding sheets through each unit at relatively high speed in a horizontal direction, and a conveyer for moving said sheets in a vertical direction and in superposed relation at reduced speed from one to another of said units, 120 said conveyer comprising a plurality of rotating elements having helical sheet engaging portions thereon.

8. In a printing machine, the combination with a plurality of printing units arranged 130

at substantially different levels, of means for feeding sheets through each unit at relatively high speed in a horizontal direction, and a conveyer for moving said sheets in a vertical direction and in superposed relation at reduced speed from one to another of said units, said conveyer comprising a plurality of rotating elements having helical sheet engaging portions thereon, the initial turns of each helix being of steeper pitch than the succeeding turns to afford clearance between successive sheets on delivery to the conveyer.

9. In a printing machine, the combination with a plurality of printing units, of means for feeding sheets in line through said units at relatively high speed, a carrier for moving said sheets in superposed relation at reduced speed between said units and intermittently operated means for positioning said sheets on said carrier.

10. In a printing machine, the combination with a plurality of printing units, of means for feeding sheets in line through said units at relatively high speed, a carrier for moving said sheets in superposed relation at reduced speed between said units and means for removing the sheets from the carrier and delivering the same to the succeeding printing unit at definite intervals, said last named means including a continuous conveyer for initiating movement of the sheets, and a reciprocating pusher operating in timed relation with said printing unit after movement is initiated.

11. In a printing machine, the combination with a plurality of printing units, of means for feeding sheets through said units at relatively high speed, and continuously moving means for engaging and moving said sheets at a reduced speed from one of said units to another.

In testimony whereof I hereunto affix my signature.

WALTER EVERETT MOLINS.
